CIGARETTE APPARATUS

William Frederick Maitland Edwards, Hinchley Wood, Esher, England, assignor to Filter Tips Limited, London, England

Application June 28, 1937, Serial No. 150,850
In Great Britain July 9, 1936

14 Claims. (Cl. 131—39)

This invention relates to the manufacture of filter tip cigarettes by uniting cigarettes or lengths of cigarette rod and stubs by means of uniting bands of cork or the like.

5 In previous methods of this kind in which the application of the uniting band is effected by rolling of the assemblage between parallel relatively movable members after the uniting band previously coated with adhesive has been brought
10 into contact with the assembled parts, the speed at which the assemblage is rolled is unduly high for a reasonably high output and tends to result in disintegration of the tobacco filling particularly at the ends of the assemblage. Furthermore, the methods of this character heretofore proposed have the disadvantage that the final seam of the uniting band is only subject to pressure momentarily and consequently insufficient time is allowed for the proper setting of the adhesive at the seam which is liable to come apart subsequently, particularly when a double length stub has to be bisected after the uniting band has been applied.

15 The present invention has among its objects
20 to provide improvements in apparatus for the production of filter tip cigarettes by a method of the character referred to whereby the disadvantages mentioned above may be obviated.

25 The expression "stubs" used herein comprises
30 filter tips, wads or plugs of any desired material or combination of materials, such stubs being generally enclosed in paper retaining wrappers although in the case of wads of spiral or other suitable formation other means may be employed
35 for retaining the formation so that the paper wrapper may be dispensed with, and also includes tubes which may be empty or filled or partially filled with filtering material and/or tobacco. The expression "cigarettes" comprises cigarettes of
40 the usual length or lengths of cigarette rod shorter or longer than the usual cigarette.

45 The invention is hereinafter described by way of example with reference to the accompanying diagrammatic drawings, in which:

Figures 1a, 1b, 1c and 1d taken together represent a side elevation partly in section illustrating one embodiment according to the invention;

50 Figure 2 is an end elevation partly in section on the line II—II, Figure 1b;

Figure 3 is a part side elevation corresponding to Figure 2;

55 Figure 4 is a view partly in section on the line IV—IV, Figure 1a;

Figure 5 is a section on the line V—V, Figure 1c;

Figure 6 is a section on the line VI—VI, Figure 1d; and

Figure 7 is a detail view illustrating a modification in the apparatus shown in Figures 1a, 1b, 1c and 1d.

5 In carrying the invention into effect and with reference to the accompanying diagrammatic drawings, pairs of cigarettes or lengths of cigarette rod are fed from a double hopper 1 into grooves 2a in a drum 2. Lengths of stub material enclosed in paper wrappers and preferably of a length equivalent to three double length stub portions are fed from a hopper 3 into grooves 4a in a drum 4 (Figures 2 and 3). The lengths of stub material are cut into double length stub portions by successively acting cutters 5 and 5a and such stub portions are, during the travel of the drum 4, ejected into grooves 6a in a carrier disc 6 which moves slower than the drum 4 and has a larger number of grooves therein. For instance, the disc 6 may have thirty-six grooves and the drum 4 may have eleven grooves, the grooves 6a in the disc 6 being conveniently of a width greater than the width of the grooves 4a so as to allow of the transfer of the stub portions from the grooves 4a to the grooves 6a when the same come into alignment, as shown more especially in Figure 3. The ejection of the stub portions into the grooves 6a may be effected by means of plungers 7 (Figure 2) actuated by springs 7a under the control of a fixed cam 8 acting on the rollers 7b. The steps 8a in the cam 8 coincide with the positions at which the grooves 4a come into alignment with the grooves 6a in the disc 6. A stop disc 6b is provided for positioning the ejected stub portions in the grooves 6a. The disc 6 is mounted on a spindle 9 provided with a gear wheel 9a and the drum 4 is mounted on a sleeve 10 provided with a gear wheel 10a of slightly less diameter, the two gear wheels 9a, 10a being geared together by gears 9b, 10b so as to rotate in the same direction but at a slightly different relative speed, the drum 4 for instance being rotated at twelve revolutions per minute and the disc 6 at eleven revolutions per minute. The stub portions are retained in the grooves 6a by the provision of fixed guides 11 which extend up to the position at which the stub portions are transferred into grooves 12a in a disc 12, transfer being ensured by the provision of fixed guides 12b as shown in Figure 1a.

45 The stub portions are delivered from the disc 12 into the grooves 2a of the drum 2 so as to lie
50 transferred into grooves 12a in a disc 12, transfer being ensured by the provision of fixed guides 12b as shown in Figure 1a.

55 The stub portions are delivered from the disc 12 into the grooves 2a of the drum 2 so as to lie

between the pairs of cigarettes therein, and the assemblages are delivered by the drum 2 to a suction transfer wheel 13.

Immediately prior to delivery of the assemblages to the suction transfer wheel 13 the lengths comprising each assemblage are butted together by the action on the ends thereof of guides 14, 14a acting on spring fingers 13a (Figure 4), one guide, for instance the guide 14a, being preferably resilient and adjustable by means of screw 14b so as to permit regulation of the pressure with which the lengths are pressed axially together. On delivery to the suction transfer wheel 13 the assemblages are held on grooved members 13b communicating through holes 13c (Figure 4) with transverse suction passages 13d which pass into communication with a hood 15 connected to a suction pipe 15a (Figures 1a and 1d).

From the suction transfer wheel 13 the assemblages are delivered to the drum 16, the hood 15 being arranged to cut off the suction through the holes 13c at this point.

A strip 27 of cork or the like is fed through pasting apparatus 18 (Figure 1c) of any suitable kind and on to the drum 16, whereon it is held by suction exerted through holes 16a, 16b (Figure 5), a hood 17 and suction pipe 17a. The strip 27 so held on the periphery of the drum 16 is cut into the necessary lengths by the action of a rotary cutter 27a which is arranged at such an angle and so operated that during the movement of the drum 16 the strip 27 is cut transversely at right angles. In other words cutter 27a is set at a slight angle in relation to the drum, the arrangement being such that the resultant cut is at right angles to the drum. In this connection it must be pointed out that this form of cutter forms no part of the invention although it is employed in the machine as constructed. Any other more usual form of cutter could be utilized.

The drum 16 is provided with slots 19' and 20' for the mounting of pairs of blades 19, 20 which, as shown in Figures 5 and 6, are carried by radially movable slider members 19a, 20a respectively provided with rollers 19b, 20b which co-operate with fixed cams 21, 22 respectively. The blades 19, 20 are formed with centrally disposed slots 19c, 20c to accommodate a rotary cutter 23 (Figure 1c) by which the assemblages are finally subdivided. The blades 19, 20 also are slotted at 19d, 20d respectively so as to render the central and outer portions of each blade resilient with respect to one another to accommodate any irregularities in the diameter or formation of the stub portions.

The cams 21 and 22 are profiled, for example as shown in Figures 1c and 1d, so that, at least during the part of the travel at which the cork or like strip 27 is fed to the drum 16 and cut by the cutter 27a and up to the point at which the assemblages are delivered from the suction transfer wheel 13 to the drum 16, the two blades 19, 20 constituting each rolling device are withdrawn flush with or within the periphery of the drum 16 so as to provide a substantially unbroken or smooth surface for the reception of the cork or like strip 27. When the assemblage is positioned on the cork strip by the suction transfer wheel 13, the two blades 19, 20 commence to move outwardly substantially in unison so that the cork strip constituting the uniting band is lapped partly around the assemblage. While the assemblage is positioned by means such as resilient fingers 24b, the blade 20 may be projected to its full extent 75 and thereafter the blade 19 may move outwards

and the blade 20 may move inwards so as to effect a rolling of the assemblage between the blades whereby the wrapping of the uniting band around the assemblage may be completed. The resilient fingers 24b referred to above are carried by an endless chain 24a passing over sprockets 24g, 24i and are guided by a fixed cam 24c. The sprockets 24g, 24i are carried by arms 24f pivotally mounted upon the member 24h, which arms may be swung for adjustment of the sprockets and endless chain. The sprocket 24i carries a gear 24o which is driven in counter-clockwise direction through the train of gear wheels 24k, 24l, 24m, 24n. Before the blade 20 commences to move inwards, the blade 19 is projected outwards to a sufficient extent to move the assemblage clear of the drum surface. As shown in Figure 7 a fixed spring plate 24e may be arranged to lap the cork 27 further around the assemblage before the blade 20 is projected, thus rendering it possible to employ blocks 24d in place of the fingers 24b on the chain 24a. During further movement of the drum 16 the blade 19 may move inwards and the blade 20 outwards so as to effect a reverse rolling of the assemblage, the arrangement preferably being such that when the assemblage reaches the cutter 23 by which it is sub-divided, it is again disposed close to or in contact with the periphery of the drum 16, the seam preferably being disposed against the blade 30 20 so that it is held thereby during the bisection of the product by the cutter 23, thereby counter-acting any tendency of the seam to open up during the cutting operation. Between the cutter 23 and the final receiving drum 25 the blade 20 may be projected and the blade 19 either held stationary or withdrawn so that the product is positively ejected into a groove 25a in the drum 25 which delivers the products to a conveyor 26 forming part of a so-called stacker.

Inasmuch as the drum 16 or equivalent conveying means may be provided with a large number of rolling units, it is possible to maintain a comparatively high output with a very low speed of movement of the conveying means which preferably moves continuously. Furthermore, when the conveying means comprises a drum the rolling movement of the blades or like members may take place over approximately three-quarters of a revolution of the drum and consequently the actual rolling of the assemblage may be effected at a very slow rotational speed of the assemblage and under a very gentle rolling pressure so that while effective wrapping is obtained there will be no tendency to disintegration of the tobacco strands.

In order to separate the sub-divided products prior to delivery to the conveyor 26 suitably curved rollers 29 driven in opposite directions are mounted so that during a part of the travel of the drum 25, the products are engaged thereby.

Furthermore, if desired, the rolling operation as described may be repeated one or more times during the travel of the drum 16 in order to consolidate the seam of the uniting bands.

Furthermore, instead of feeding the cork or the like on to the periphery of the drum 16, the lengths of previously pasted cork may be applied to the assemblages while they are carried on the suction transfer wheel 13, in which case the provision of suction means on the drum 16 is unnecessary. For example, the suction transfer wheel 13 may be arranged to carry the assemblages away from the assembly drum 2 into contact with previously pasted pieces of cork car-

ried by a separate cork-conveying drum on which the cork is held by suction. At the moment of contact the suction acting on the cork is cut off so that the cork adhering to the assemblage is released and is carried with the assemblage into position in contact with or adjacent the periphery of the drum 16, whereupon the cork is wrapped partially around the assemblage by the outward projection of the blades 19, 20.

10 The expression "cork" used herein comprises any suitable uniting material.

It will be understood that the invention is not limited to the particular embodiment hereinbefore described. For example, in place of the drum 16, an endless chain structure may be employed, in which case the rolling blades would reciprocate in planes perpendicular to the plane of the chain structure and such reciprocation could be effected by suitably shaped stationary 20 ramps or cams.

What I claim is:

1. Apparatus for the manufacture of filter tip cigarettes by wrapping a uniting band about an assemblage of cigarette and stub portions, comprising conveying means on which the wrapping of the uniting band about the assemblage is effected, members mounted on said conveying means to engage opposite sides of each assemblage, said members being reciprocatable in planes intersecting the path of movement of the conveying means whereby the assemblage may be rolled between the said members about its own axis, and means for effecting the reciprocatable movement of the said members.

2. Apparatus for the manufacture of filter tip cigarettes by wrapping a uniting band about an assemblage of cigarette and stub portions, comprising a continuously moving conveyor on which the wrapping of the uniting band about the assemblage is effected, members mounted on the said conveyor, said members being reciprocatable in planes intersecting the path of movement of the said conveyor, and cam means for effecting reciprocatory movement of the said members so that assemblages engaged thereby are rolled to complete the wrapping of the uniting bands about the assemblages during movement of the said conveyor.

3. Apparatus for the manufacture of filter tip cigarettes by wrapping a uniting band about an assemblage of cigarette and stub portions, comprising means acting on the uniting band by relative movement of the assemblage and said means towards one another to lap the band partly around the assemblage, said means including two relatively movable members, and means for effecting the relative movement of said members to roll the assemblage therebetween for the completion of the wrapping operation.

4. Apparatus for the manufacture of filter tip cigarettes by wrapping a uniting band about an assemblage of cigarette and stub portions, comprising conveying means such as a drum, blade-like members carried thereby and mounted so as to be movable in planes intersecting the path of movement of the said conveying means, means for feeding an assemblage into wrapping position and cam means for operating the blade-like members so that a pair thereof is projected to wrap a uniting band partly around an assemblage fed into position and for thereafter effecting relative movement of the blade-like members to complete the wrapping operation by rolling of the assemblage.

5. Apparatus as claimed in claim 4, wherein the said cam means are fixed.

6. Apparatus as claimed in claim 4, wherein the conveying means is provided with perforations along part of its surface, and suction means communicating with said perforations and serving to retain the uniting bands in position on the conveying means prior to the wrapping operation.

7. Apparatus for the manufacture of filter tip 10 cigarettes by wrapping a uniting band about an assemblage of cigarette and stub portions, comprising conveying means, pairs of members carried thereby and mounted so as to be reciprocatable in planes intersecting the path of movement of the said conveying means, assembly means, a rotary suction transfer device receiving the assemblages from the assembly means and delivering said assemblages between the pairs of said members, and means for effecting relative 20 reciprocatory movement of the said members to effect the wrapping of the uniting bands around the assemblages by rolling of the assemblages between the said members.

8. Apparatus for the manufacture of filter tip 25 cigarettes by wrapping a uniting band about an assemblage of cigarette and stub portions, comprising conveying means, pairs of members carried thereby and mounted so as to be reciprocatable in planes intersecting the path of movement of the said conveying means, assembly means, a rotary suction transfer device receiving the assemblages from the assembly means and delivering said assemblages between the pairs of said members, resilient members mounted 30 on said rotary suction transfer device so as to be capable of engaging the ends of the assemblages carried thereby, relatively inclined fixed guides acting on the said resilient members to cause the same to press the parts of the assemblage axially towards one another, and means for effecting relative reciprocatory movement of the said members to effect the wrapping of the uniting bands around the assemblages by rolling of the assemblages between the said members.

9. Apparatus for the manufacture of filter tip 45 cigarettes by wrapping a uniting band about an assemblage of cigarette and stub portions, comprising, an assembly drum having grooves to receive pairs of cigarettes axially spaced apart, 50 a hopper for supplying multiple lengths of stub material, a drum arranged to receive the lengths of stub material, cutters associated with the said drum to sub-divide the lengths of stub material, a disc coaxial with said last-mentioned drum and 55 provided with grooves, ejecting means operating during the rotation of the last-mentioned drum to feed the sub-divided stub portions into the grooves in said disc, means for transferring the stub portions from the said disc and for delivering the same between the pairs of cigarettes on the said assembly drum, a rotary suction transfer device receiving the assemblages from the assembly drum, conveying means receiving the assemblages from the said suction transfer device, members mounted on said conveying means to engage opposite sides of each assemblage said members being reciprocatable in planes intersecting the path of movement of the conveying means, and means for effecting relative reciprocatory movement of the said members for rolling the assemblage about its axis to complete the wrapping operation.

10. Apparatus for the manufacture of filter tip 70 cigarettes by wrapping a uniting band about an 75

- assemblage of cigarette and stub portions, comprising, an assembly drum having grooves to receive pairs of cigarettes spaced apart, a hopper for supplying multiple lengths of stub material, a drum arranged to receive the lengths of stub material, cutters associated with the said drum to sub-divide the lengths of stub material, a disc coaxial with said last-mentioned drum and provided with grooves, ejecting means operating during the rotation of the last-mentioned drum to feed the sub-divided stub portions into the grooves in said disc, means for transferring the stub portions from the said disc and for delivering the same between the pairs of cigarettes on the said assembly drum, a rotary suction transfer device receiving the assemblages from the assembly drum, relatively inclined fixed guides associated with the said suction transfer device and acting to press the parts of the assemblage axially into contact, means for adjusting one of said guides, conveying means receiving the assemblages from the said suction transfer device, members mounted on said conveying means to engage opposite sides of each assemblage, said members being reciprocatable in planes intersecting the path of movement of the conveying means, and means for effecting relative reciprocatory movement of the said members for rolling the assemblage about its axis to complete the wrapping operation.
11. Apparatus for the manufacture of filter tip cigarettes by wrapping a uniting band about an assemblage of cigarette and stub portions, comprising conveying means such as a drum, blade-like members carried thereby and mounted so as to be movable in planes intersecting the path of movement of the said conveying means, said blade-like members being slotted to provide relatively resilient central and outer portions, means for feeding an assemblage into wrapping position and cam means for operating the blade-like members so that a pair thereof is projected to wrap a uniting band partly around an assemblage fed into position, and so that said blade-like members are thereafter moved relatively to one another to complete the wrapping operation by rolling of the assemblage therebetween.
12. Apparatus for the manufacture of filter tip cigarettes by wrapping a uniting band about an assemblage of cigarette and stub portions, comprising a rotary conveyor provided with slots in

the periphery thereof, pairs of radially slideable members carried by said rotary conveyor, two fixed cams one at each end of said rotary conveyor co-operating with the respective radially slideable members, blades mounted on said slideable members and projectible through the slots in the periphery of the said rotary conveyor, perforations intermediate the said slots, means for feeding pasted uniting bands to the periphery of the said rotary conveyor so as to overlie said perforations, and means for positioning assembled cigarettes and stubs on said uniting bands, said cams being profiled so that each pair of blades is projected first to wrap a uniting band partly around the respective assemblage and so as thereafter to effect relative movement of the blades to complete the wrapping operation by rolling of the assemblage therebetween.

13. Apparatus as claimed in claim 8, wherein one of the relatively inclined fixed guides is resilient, and means for adjusting said resilient guide for the purpose of regulating the degree of axial pressure with which the lengths constituting each assemblage are caused to abut one another.

14. Apparatus for the manufacture of filter tip cigarettes by wrapping a uniting band about an assemblage of cigarette and stub portions, comprising conveying means, pairs of members carried thereby and mounted so as to be reciprocatable in planes intersecting the path of movement of the said conveying means, assembly means, a rotary suction transfer device receiving the assemblages from the assembly means and delivering said assemblages between the pairs of said members, relatively inclined fixed guides arranged to act on the ends of the assemblage while carried by said rotary suction transfer device, means for effecting relative reciprocatory movement of the said members to effect the wrapping of the uniting bands around the assemblages by rolling of the assemblages between the said members, one of the relatively inclined fixed guides being resilient, and means for adjusting said resilient guide for the purpose of regulating the degree of axial pressure with which the lengths constituting each assemblage are caused to abut one another.

WILLIAM FREDERICK

MAITLAND EDWARDS.

50
